UNITED STATES PATENT OFFICE.

HUGH P. MAGONE, OF ANACONDA, MONTANA.

WATER-MOTOR OR PROPELLER.

1,230,191.

Specification of Letters Patent. Patented June 19, 1917.

Application filed June 7, 1916. Serial No. 102,280.

To all whom it may concern:

Be it known that I, HUGH P. MAGONE, a citizen of the United States, residing at Anaconda, in the county of Deerlodge and State of Montana, have invented certain new and useful Improvements in Water-Motors or Propellers, of which the following is a specification, reference being had to the accompanying drawings.

10 This invention relates to devices for either securing power from a stream of water or for propelling bodies by engagement with a relatively fixed body of water, and particularly to a motor or propeller of this character in which endless chains are used passing around suitable power receiving or delivering wheels, these chains carrying blades.

15 A further object of the invention is to provide, in a motor of this character, means for supporting the chains so that they will travel on a fixed and endless path, and further to provide means whereby the blades and chains may properly turn or pass from the upper flight of the chains to the lower flight thereof.

20 Other objects have to do with the details of construction of an apparatus of this character as will hereafter more fully appear.

25 My invention is illustrated in the accompanying drawings, wherein:

Figure 1 is a side elevation of my improved water motor;

Fig. 2 is an end view, the flume being in section;

30 Fig. 3 is a perspective detail view of one of the carriages and blades and a portion of the track;

Fig. 4 is an under side plan view of the construction shown in Fig. 3;

35 Fig. 5 is a perspective detail view of one of the blades showing the manner in which it is connected to the sprocket chains 17;

Fig. 6 is a side elevation of the hull of a boat showing my invention applied thereto as a motor; and

40 Fig. 7 is an end view of the construction shown in Fig. 6.

45 In Figs. 1 to 5, I show my invention as applied to receiving power from a running stream, and I will refer first to this application of my invention. In these Figs. 1 to 5, 10 designates a flume having the side boards 11 whereby to direct the flow of water through a relatively narrow channel. Extending upward from the side boards 11 are the standards or supports 12, four

of which are illustrated as being used. Mounted upon one pair of these supports 12 at one end of the flume is a shaft 13 carrying the relatively smooth, spaced wheels 14, and rotatably mounted in the other supporting members 12 is the shaft 15 carrying the spaced sprocket wheels 16. Passing over these sprocket wheels and over the smooth faced wheels are the endless sprocket chains 17. These wheels 13 and 16 are of such diameter that the lower flight of the sprocket chains is just above the level of the upper edges of the flume boards 11.

50 Attached to the supports 12 in any suitable manner are the oppositely disposed pairs of track rods 18 and 19. Each of these track rods is approximately elliptical in form having upper and lower flights joined by curved ends. These track rods are supported slightly outward from the inner faces of the supports or standards 12.

55 Operating between these tracks 17 and 18 are a plurality of carriages each carrying a blade. Each carriage comprises the transversely extending axles as they may be termed, 20 and 21, each axle having at its ends the grooved wheels 22 which are adapted to engage between the track rods 18 and 19 and engage with one of these track rods. The axles 20 and 21 are connected by longitudinally extending links 23 pivotally connected to the axles so as to have free oscillation. Mounted upon the axle 21 and extending out therefrom is a blade 24 which is held in a position perpendicular to the path of movement of the blade carriage by means of braces 25 which extend downward to the axle 20 and are attached to this axle in any suitable manner. The upper ends of these braces are attached to the outer ends of the blades upon the rear face thereof. The chain 17, as illustrated most clearly in Fig. 3, is attached, as at 26, to the axle 21, but the chain is not attached to the axle 20. The track rods 18 and 19 are so spaced from each other that the wheels 22 will run freely upon one of the track rods but be guided by the other track rod but not rotatably engaged therewith.

60 In the operation of this invention as a current motor, the shaft 16 is connected to transmit power. As the force of the current strikes the several paddles or blades 24 in the passage of water through the flume, the blades will be caused to travel in the direction of the arrow, Fig. 1, and in a fixed

elliptical path. As the carriage for each blade moves along the upper flight, the wheels 22 will engage with the track rod 19. As the carriage moves along the lower flight, however, the rear wheels 22, those on the axle 21, will engage with the track rod 18, but the forward wheels, those on the axle 20, will engage with the track rod 19, due to the pressure on the paddle. When 10 the blades reach the turning point of the tracks the wheels will follow the curvature of the tracks but the links 23 will extend diagonally across the arc of movement of the wheels as illustrated in Fig. 1. Thus 15 there is no binding action of the carriages on the track but the several carriages move perfectly freely thereon with but a minimum of frictional resistance and a maximum of efficiency. The blades strike the 20 water or dip into the water very quickly, that is, take their vertical position within the water very quickly so as to receive the impact of the current almost immediately that they enter the chute or flume, so that 25 there is very little loss of power at the time the blade enters the flume. In the same manner the blade leaves the water very quickly so that there is but little reaction at the time the blade leaves it.

30 While I have heretofore described my device as intended to be driven by water, it is also obvious that it may be used as a propeller as illustrated in Figs. 6 and 7. In this construction beams or supports 27 are 35 shown as extending across the vessel and supporting the supports 12^a which are the equivalent of the supports 12. Under these circumstances the shaft 15^a will be driven by power instead of receiving power from 40 the blades and the blades will engage with the water and urge the vessel or other object forward. It will be seen from Fig. 6 that the upper flight of blades is always above the water line, while the lower flight dips into 45 the water. Inasmuch as the construction of the remainder of the apparatus is the same as in the former case with simply a reversal of the action of the mechanism, it is not believed that detail views or descriptions are 50 necessary.

The usefulness of the device for propelling vessels will be apparent. The propellers so constructed will be very effective and are particularly adapted for driving 55 boats in shallow water. Throughout the claims I shall refer to my construction as a water motor. It is to be understood that this term includes a device which is either operated by the force of running water or 60 which operates upon water in the manner of a propeller.

Having described the invention, what I claim is:

1. A motor of the character described including supporting members, oppositely dis-

posed shafts mounted thereon, wheels mounted upon said shafts, sprocket chains passing over the wheels, a pair of tracks mounted upon said supports comprising inner and outer track members, said tracks extending 70 parallel to each other and parallel to the path of the sprocket chains, carriages comprising forward and rear axles, wheels mounted upon the axles and operatively engaging said track members, links pivotally connecting the axles, blades attached to the forward axles and normally extending perpendicularly to the sprocket chains, braces extending from the blades to the rear-most axles, said sprocket chains being operatively connected to the forward axles, said connection permitting the blades to rotate with respect to said sprocket chains. 75

2. A motor of the character described including supporting members, oppositely disposed shafts mounted thereon, wheels mounted upon said shafts, one pair of said wheels being sprocket wheels, parallel endless sprocket chains passing over said wheels, a pair of tracks mounted upon said supports comprising inner and outer track rods, carriages comprising forward and rear axles, wheels mounted upon the axles, and links pivotally connecting the axles and blades attached to the forward axles and extending perpendicularly to the sprocket chains, and braces extending from the outer ends of the blades to the rear-most axles. 80

3. In a motor of the character described, supporting members, shafts mounted in said supporting members, plane faced wheels carried upon one of said shafts, sprocket wheels carried upon the other of said shafts, parallel endless sprocket chains passing over said sprocket wheels and the corresponding plane faced wheels, outer and inner pairs of track rods mounted upon said supports and extending parallel to the path of movement of the sprocket chains, a plurality of axles attached to said chains and having 90 grooved wheels engaging the track rods, an outstanding plate mounted upon each axle, a rear axle for each plate, links pivotally connecting the rear axle to the corresponding forward axle, said rear axle having 95 grooved wheels engaging between said track rods, and braces connecting the rear axles to the outer ends of the blades. 100

4. In a motor of the character described, supporting members, oppositely disposed shafts mounted thereon, wheels carried by said shafts, parallel endless sprocket chains passing over the wheels and moving in a substantially elliptical path, a pair of track rods operatively supported upon each supporting member in spaced relation to each other, each pair of tracks extending parallel to the upper and lower flights of its corresponding sprocket chain and extending concentrically to the side wheels, blades piv- 110 115 120 125 130

otally connected to the sprocket chains and normally extending perpendicularly thereto, forward and rear wheels engaging between said tracks, links pivotally connecting the forward and rear wheels, and braces extending from the blades and operatively connected to the rear wheels.

In testimony whereof I hereunto affix my signature in the presence of two witnesses.

HUGH P. MAGONE.
